UNITED STATES PATENT OFFICE

FERDINAND J. TILLMAN, OF ST. LOUIS, MISSOURI, ASSIGNOR TO REMINGTON RAND INC., OF NEW YORK, N. Y., A CORPORATION OF DELAWARE

CARD FINDING AND SEPARATING DEVICE

Application filed June 3, 1919. Serial No. 301,560.

The primary object of this invention is to provide an improved simple mechanism for operating on a plurality of vertically held index cards relative to finding and moving a 5 particular card from the plurality of cards.

Another object is in providing an improved construction of card-engaging or lifting members in which a pair of them is adapted to be moved longitudinally and 10 transversely beneath a plurality of cards so that said pair of card-engaging members can be adapted to work on a plurality of cards relative to selecting and moving any card of the plurality of cards.

15 A further object is in providing an improved card finding and moving device in which the operating parts thereof are controllable in both directions of movement, either forwardly or rearwardly relative to 20 moving the operating parts in the desired section for locating and moving a particular card, and in which none of the parts have to be set up or returned for the next operation in acquiring another one or more cards, as 25 the parts are always active towards approaching a desired section of cards, whether moved forwardly or rearwardly.

A still further object is in providing improved means whereby the next adjacent 30 card in order relative to the desired card selected is also moved upwardly, thereby providing a guide or pilot card for the returning of the desired card after it has been removed from the pack or plurality of cards.

35 Another still further object is in providing improved means for retaining the cards in their upwardly moved positions.

Other and further objects will appear in the specification and be specifically pointed 40 out in the appended claims, reference being had to the accompanying drawings exemplifying the invention, and in which,

Figure 1 is a plan view, partly diagrammatic, the plurality of cards on which the 45 device is capable of operating being omitted so as to disclose the mechanism.

Figure 2 is a front elevation, partly in section of Fig. 1.

Figure 3 is a fragmentary section taken approximately on the line III--III of Fig. 1,

said figure disclosing the first section of cards in place in the receptacle.

Figure 4 is an enlarged transverse section taken approximately on the line IV--IV of Fig. 1.

Figure 5 is a fragmentary horizontal section taken on the line V--V of Fig. 4.

Figure 6 is an enlarged fragmentary plan view of a portion of the card holding receptacle, having the intermediate part broken away.

Figure 7 is a diagrammatic view disclosing the lower portions of a group of ten cards which are of special design, the mass of cards to be used in this improved device consisting of several like groups.

Referring to the drawings, this improved device comprises an open top receptacle 1 which is mounted on a base 2, said receptacle being divided into a plurality of card-holding compartments 3 which are formed by the partitions 4, each compartment containing a group of ten vertically held cards, the lower edges of which rest upon longitudinally arranged sills 5^a, each card being provided with a pair of downwardly projecting portions 5, the pairs of projections of said cards being equally spaced apart.

Arranged longitudinally beneath the cards is a pair of parallelly arranged bars 6, the ends of said bars being secured in end frames 7, each end frame being slidably mounted on a transversely arranged support 8.

Slidably mounted on each bar 6 is a sleeve 9, said sleeves being tied together by a cross member 10. Swingingly mounted on one of the sleeves 9 is a series of card-lifting members 11, each having a card-engaging portion 12, and swingingly mounted on the other sleeve 9 is a series of card-moving members 13, each having card-engaging portions 14, said card moving members 11 and 13 being arranged in pairs and approximately side-lapping each other in pairs, each pair of card-moving members being swingingly secured to each other by a pin and slot connection 15.

These pairs of card moving members are spaced and held at equal distances apart by the sleeves 9 on which they are mounted, and

the card-engaging portions 12 and 14 thereof are of such a width whereby they under-
5 extend the approximate width of a card compartment 3, the engaging portion 12 of the moving member 11 being wider than the en-

6 gaging portion 14 of the member 13, so that the engaging portion 12 will extend into the next adjacent compartment towards a higher order of cards, all of which will be herein-
10 after brought out.

10 Longitudinally arranged beneath the card-moving members 11 and 13 is a supporting bar 16, and swingingly mounted on said bar are a series of equally spaced apart lifting members 17, each lifting member having a horizontally and longitudinally extending portion 18 formed at one end, each extending portion 18 being related to a respective pair of card-moving members 11 and 13, and being
15 of a length whereby they underlap the travelling distance of their respective pair of card-moving members with which they are cooperable.

20 Parallelling the bar 16 is a supporting bar 19 which slidably supports a sleeve 20, and rigidly secured to said sleeve is a series of spaced-apart approximately horizontally extending arms 21, each having an upturned portion 22, each arm being related to a respective lifting member 17.

25 Mounted on the sleeve 20 is a movable collar 23, having a depending portion 24 which is secured to an endless cable 25, said cable passing around a series of pulleys 26.

30 Located adjacent the front wall 27 of the receptacle 1 is a dial plate 28, having a series of lever slots 29, 30 and 31, each slot on one edge being provided with ten notches, each set of notches indicating a number ranging from cipher to nine, as shown in Fig. 1.

35 Extending through the slot 29 of the dial 28 is an operating lever 32, said lever being rigidly secured to one end of a horizontally arranged shaft 33, and formed on the opposite end of said lever is the segmental gear 34.

40 The shaft 33 extends beneath the plurality of index cards located in the receptacle 1, and rigidly secured to said shaft is a pair of gear segments 35, one of which is located in each 45 of the end walls 27 and 36 of the receptacle 1, each segment 35 meshing with an inverted rack 37, each rack being supported by one of the end frames 7.

45 Extending through the slot 30 of the dial 50 plate 28 is an operating lever 38 which is loosely mounted on the shaft 33, the opposite end of said lever having a segmental gear 39, and formed in said lever adjacent the segmental gear 39 is a slot 40, through which extends a portion of a sliding block 41, said block being mounted in the guideway 42.

55 Secured to said block 41 is an endless cable 43 which passes around a series of pulleys 44, said cable also being secured to a longitudinally sliding block 45 which is mounted between

guideways 46, and extending upwardly from said block 45 is a shifting arm 47 which engages the tie rod 10 of the sleeves 9 on which the card-moving members 11 and 13 are mounted.

60 Extending through the slot 31 of the dial plate 28 is a lever 48 which is swingingly mounted on the shaft 33, the opposite end of said lever bearing a segmental gear 49 and a slot similar to that described relative to the lever 38, and engaging in the slot of the lever 48 is a sliding block 50 which is mounted in a guideway 51, said block 50 being secured to the endless cable 25 which is related to the collar 23 of the sleeve 20.

65 Rigidly secured to one end of the bar 19 adjacent the front end wall 27 of the receptacle 1 is a striking lever 52, the opposite end of said lever carrying a pin 53, said pin 53 being co-operable with the cam surface 54 of a locking pawl 55, the engaging edge of said pawl being wide enough to engage across the faces of all of the segmental gears 34, 39 and 49 of the respective operating levers 32, 38 and 48.

70 In leading up to the operation of this improved device, the mechanisms towards effecting a result relative to finding and moving or separating a desired card from a plurality of cards may well be grouped in the following order, hundreds, tens and units; as this device is capable of selecting any card from a plurality of one thousand cards, the mechanism for setting the operating parts pertaining to a hundred is comprised of the operating lever 48, endless cable 25 to which it is related, slideable sleeve 20, and the arms 21 of which there are ten.

75 The tens mechanism comprises lever 38, related cable 43, sliding block 45, shifting arm 47, and the card-moving member carriage 56, said card-moving member carriage consisting of all of the pairs of card-moving members 11 and 13 and the sliding sleeves 9 on which they are mounted.

80 The movement of said carriage as relating to the tens mechanism is longitudinal. The units mechanism comprises lever 32, shaft 33, and pair of segments 35 mounted thereon, and the end frames 7 of the carriage 56, supporting the racks 37 with which the segments 35 are in mesh, the operation of the units mechanism only including the transverse travel of the carriage 56.

85 The receptacle 1 of this improved device is adapted to contain one thousand index cards, which will be numbered in order, running from cipher to nine hundred ninety-nine, the set of one thousand cards being arranged in groups of one hundred, ranging from cipher to ninety-nine, one hundred to one hundred and ninety-nine, two hundred to two hundred and ninety-nine, and so on, and occupying the spaces in order as indicated by A, Fig. 1.

These groups of one hundred cards are then subdivided into groups of ten cards each, each group of ten cards occupying a compartment 3, each group of ten cards being further designated by B, as shown in Fig. 1, the cards in each ten card group being consecutively numbered as from cipher to nine, ten to nineteen, twenty to twenty-nine, up to the card ending in ninety-nine of each one hundred card group.

As already related, each card is provided with a pair of equally spaced apart depending projections 5, although the pairs of projections of each card are staggered in relation to the pairs of projections of the cards next adjacent so that the pairs of projections of a sub-group of ten cards will be longitudinally staggered, see Figs. 4 and 7.

From an inspection of Fig. 7, it will be noted that all of the cards except the cipher card of each ten card group has a depending shoulder 57 formed adjacent each right-hand depending projection 5, the exact position of each shoulder 57 being in longitudinal alinement with the right-hand projection 5 of the card next ahead, for instance the unit two card has its shoulder 57 in longitudinal alinement with the projection 5 of the unit card one, whereas the shoulder 57 of the unit card one is in alinement with the right-hand projection 5 of the cipher unit card. The purpose of the shoulders of the cards is for lifting the upper right-hand corner of the next highest card in order adjacent the desired card, or in other words, elevate two cards at one time, in which the desired card will be in front of the highest numbered card lifted, so that when the desired card is removed from the plurality of cards, the remaining projecting card will serve as a guiding back or pilot card for the returning of the desired card.

From the aforesaid description relative to the shoulders 57 of each card it appears that when a card ending with a cipher is operated on, the card bearing number one will also be moved upwardly, said card numbering one serving as a pilot card to the cipher card, whereas when number one is the desired card operated on, number two card will be brought up as the pilot card, and so on all the way through to the nine card, in which instance the next cipher card in order as the high number will be brought up as the pilot card to the nine card, although each cipher card has a depending projection 58 in lieu of a shoulder 57, said projection 58 being in longitudinal alinement with the right hand projection of a card 9, the cipher pilot card to the desired card 9 being shown in dotted lines in Fig. 7.

As shown in Figs. 1 and 2 of the drawings, the operating levers 32, 38 and 48 are set in a position for actuation relative to the lowest numbered card which is a cipher card, in which position the spring-pressed detents 59

thereof are each engaging respective cipher notches. In this position of the levers, it will be noted from an inspection of Fig. 1, that the first arm 21 in order as relating to the hundreds mechanism, which is further designated as C, is directly beneath the lifting member 17 which relates to the first set of one hundred cards, and in which the longitudinally extending portion 18 of said member 17 is in under-engaging position relative to the first pair of card moving members 11 and 13, the card engaging portions 12 and 14 of said lifting members being directly beneath the projections 5 of the cipher card.

In order to effect upward movement of said cipher card, the striking lever 52 is engaged and pressed downwardly by the operator, and inasmuch as said lever is rigidly secured to the shaft 19, and said sleeve being slidably secured to the shaft by the key 60 all of the arms 21 carried by the sleeve 20 of said shaft, will be moved upwardly, and since the arm C of the plurality of arms 21 is the only one placed in a position for upward engagement with the lifting arm 17, said lifting arm 17 of the first hundred group will be elevated, and the portion 18 thereof will engage and elevate the card-moving member 11, and incidentally the mating card-moving member 13 through the agent of the pin 15 which couples them together, thereby causing the portions 12 and 14 of said pair of card-moving members 11 and 13 to engage and elevate the pair of projections 5 of the cipher card, and owing to the fact that the engaging portion 12 of the card-moving member 11 extends across all of the card units of a sub-group of ten cards, said engaging portion 12 engages the shoulder 57 of the next higher card number one in order, thereby elevating the right upper hand edge of said card number one simultaneous with the elevating of the cipher card. As the striking lever 52 was moved downwardly for effecting upward movement to the desired card and its adjacent pilot card, the pin 53 carried by the lower end of said lever engaged the cam surface 54 of the pawl 55, thereby elevating said pawl, and engaging it between the teeth of the segments 34, 39 and 49 of all of the operating levers 32, 38 and 48 respectively, and effecting a lock to said operating levers, and incidentally the mechanisms pertaining thereto so that none of the operating parts of the lever mechanisms can be operated until the card-moving operation has been completed.

After the striking lever 52 has been released, said lever and the arms 21 pertaining thereto will return to their normal positions by gravity, as well as the lifting member 17 and the pair of card-moving members 11 and 13.

From the aforesaid it is to be noted that in order to acquire the cipher card, each operat-

- ing lever 32, 38 and 48 must register with a cipher on the dial plate 28. Assuming it is desired to acquire card number eight hundred and seventy three; the lever 48 will be moved to a registering position relative to the numeral 8 of the dial plate, which movement of said lever will cause a pull to be exerted on the endless cable 25, thereby sliding the sleeve 20 bearing the series of arms 21 of the hundreds mechanism until the arm 21, designated as D, and pertaining to the eight hundred section or group of cards is moved to a position beneath the lifting member 17, further designated as E.
- 15 The lever 38 is then moved to a position registering with the numeral 7 of the dial plate, which movement exerted a pull on the endless cable 43, thereby moving the sliding block 45 and vertical portion 47 forwardly, and since said portion 47 is in engagement with the tie rod 10 of the carriage 56, thereby moving all of the pairs of card-lifting members rearwardly until the pair of card-lifting members, designated as F, is brought to a position beneath the seventh ten card group of the eight hundred card section, the lever 32 is then manipulated and moved to a position of registration with the numeral three of the dial plate, the movement of said lever rock-
25 ing the shaft 33, and causing the gear segments 35 to impart motion to the racks 37 of the end frames 7 of the carriage 56, thereby moving said carriage transversely to a position wherein the card-engaging portions 12 and 14 of the pair of card-moving members F will be arranged in a position directly beneath the pair of projections 5 of card ending with the numeral 3 of the seventh group of cards of said eight hundred card group or section, the lifting of the desired card aforementioned as number eight hundred and seventy three is then effected by downward pressure on the striking lever 52, as already related, in which the arm D will be elevated, thereby applying upward movement to the lifting member E so that upward movement will be applied to the pair of card-moving members F, in which case card number eight hundred and seventy three will be elevated in an upright position, whereas card number eight hundred and seventy-four will be angularly elevated in order to serve as a pilot card thereto.
- 35 Assuming that it is desired to acquire a card lesser in number than eight hundred and seventy-three, such as card number four hundred and fifty, it will be noted that rearward movement of the lever 48 will be required in order to return the arm 21 further designated as G, to its alining position beneath the lifting member H, owing to the fact that said arm G was moved beyond its respective lifting member H when the hundredth mechanism was previously moved to a position of

actuation relative to acquiring card number eight hundred and seventy-three.

In this connection it is to be noted that on account of the operating levers 32, 38 and 48 being directly connected with the mechanisms which they are adapted to operate, the hundreds, tens and units mechanisms, in no matter what direction they are moved, whether forwardly or rearwardly, longitudinally and transversely, (as their movement in either direction, forwardly or rearwardly is not an idle movement, but an active movement towards moving the operating parts to a position of actuation relative to any card,) always set the parts regardless of the designating positions they are left in after a desired card has been acquired, and in which case none of the mechanisms have to be reset or returned for effecting a second result or successive results.

80 From the aforesaid operation relative to the working of the levers 32, 38 and 48, it is to be noted that three settings of said levers are necessary in order to locate the three selecting mechanisms, namely hundreds mechanism, tens mechanism and units mechanism.

85 As a further illustration relative to the three locating operations to be carried out, if it is desired to obtain card number nine which is located in the first group B of ten cards, the levers 48 and 38 will each register with its respective cipher mark on the dial plate, whereas the lever 32 will have to be shifted to nine on the dial.

90 In the case already illustrated relative to obtaining the cipher or first card in the first set of tens, each of the levers 32, 38 and 48 have to register with their respective dial ciphers.

95 Assuming it is desired to obtain card number nineteen, which is located in the section ten card group B in order, the lever 48 will register with its dial cipher, whereas the lever 38 will register with its dial numeral one and the lever 32 register with its dial numeral nine.

100 As a further illustration of an advantage of this improved device, and returning again to the acquiring of cards numbered cipher, nine and nineteen, assuming the operator first set the operating levers 32, 38 and 48 on respective dial ciphers for acquiring the cipher card, it is only necessary for him to shift the lever 32 to nine to locate the carriage 56 transversely in order to acquire the nine card, and after he has acquired the nine card, it will only be necessary for him to shift the operating lever 38 for moving the carriage 56 longitudinally so that the relatable pair of card-moving members of the carriage will be placed in longitudinal location as called for by the dial numeral one relative to said lever 38 for acquiring said nineteen.

105 Furthermore, in a device of this improved character relative to the finding and moving of desired cards from a plurality of cards, an

operator can manipulate the device with great rapidity on account of the fact that it is immaterial which of the levers 32, 38 and 48 are moved first for locating the desired units, tens or hundreds of the plurality of cards.

As it is well known that the idea of three numbers is memorized at a glance, therefore the operator can manipulate the operating levers in a reverse order or the central number or lever can be moved first, as suits his judgment relative to the juxtaposition of his operating fingers, or two or all of the operating levers can be moved at the same time. In order to hold and retain the cards as they are moved or elevated by the operating mechanisms, a series of spring-actuated rollers 61 are mounted in each side wall of the receptacle 1, there being a pair of opposing rollers for each compartment 3, said rollers normally resting in recesses 62, one of which is formed in each of the side edges of each index card, and when all of the cards are in normal positions resting on the sills 5^a, the recesses 62 are in horizontal alinement, see Figs. 3 and 4.

The upholding action of the rollers 61 is brought about as each desired card is elevated, in which the upward movement of the card will force the rollers from engagement with the recesses 62 of the cards, and the cards are elevated to positions above the rollers so as to allow the rollers 61 to move inwardly to their normal positions beneath the lower corners of each elevated card, as shown in Fig. 4, and inasmuch as the elevated pilot card of each index card is only lifted from one side, only one lower edge of each elevated pilot card will be engaged by the roller.

Rigidly secured on the forward end of the supporting bar 16 is a checking lever 63, said lever being for the purpose of rocking the bar 16 and elevating all of the lifting members 17 in unison. These lifting members 17, of which there are ten, are loosely mounted on the support 16 relative to being moved upwardly by the respective arms 21 which form part of the hundreds mechanism, but when the lever 63 is moved downwardly in a left hand direction, each pin 64 which is secured to the support 16, and there being a pin 50 mounted in a slot 65 of each respective lifting member 17, will bear on the hub portion of each lifting member 17 and cause the extending portion 18 of each lifting member to be swung upwardly in unison, thereby effecting an upward movement of all of the ten pairs of card-moving members 11 and 13, in which case a card of each sub-group of ten cards under which each pair of respective card-moving members is located, will be elevated. For instance, with respect to the location of the pairs of card-moving members shown in Fig. 1, the first card of each hundred group ending with a cipher will be elevated, that is the cipher or first card of the first hundred set, the one hundred card of the next

hundred set, and so on. This operation of the checking lever 63 relative to the upwardly moving in unison of all of the lifting members 17 and related pairs of card-moving members is for the purpose of checking the cards relative to locating missing cards. If it is desired to go farther and check up the first order of cards ending with the numeral 1 as relating to cards number one, one hundred and one, two hundred and one, and so forth, the unit lever 32 will be moved from register with the position of cipher to a position of register with numeral one of the dial plate, and the checking lever 63 is again operated.

From the aforementioned checking operation, it is to be noted that ten cards at a time can be brought up in unison. For returning a number of cards after they have been elevated relative to the checking operation, a pressing element 64 is provided which is shown in Figs. 2 and 4, and is comprised of a pair of longitudinally and parallelly arranged members 65 carried by the frame 66, said frame being swingingly secured at 67 to one side of the receptacle 1 so that the pressing element can be swung to and from the upper edges of the plurality of cards, the members 65 of said pressing element when engaged and pressed against the tops of the uplifted cards forcing them down together to seating positions on the sills 5^a and in their normal positions.

What I claim is:

1. In a card separating device, the combination of a longitudinally movable member, a carriage adapted to longitudinal and transverse travel, a pair of card-moving members carried by said carriage having their card-engaging portions spaced apart a given distance, and means cooperable with said longitudinally movable member and said card-moving members for actuating said card-moving members.

2. In a card separating device, a receptacle containing a plurality of cards, a member movable longitudinally beneath said cards, a pair of card-moving members adapted to be moved longitudinally and transversely above said longitudinally movable member and held against movement towards or from each other, and cooperating means located between said longitudinally movable member and said card-moving members for allowing said longitudinally movable member to become active on said card-moving members.

3. A card separating device comprising a receptacle containing a plurality of cards, each having a pair of depending projections, the pairs of projections of each card being spaced equally apart, and a pair of card-moving members arranged beneath the projections of said cards, adapted to longitudinal and transverse travel for operating on the pairs of projections of said cards.

4. A card separating device comprising a receptacle containing a plurality of cards, each card having a pair of depending projections, the pairs of projections of each card being spaced equally apart, a pair of card-moving members arranged beneath the projections of said cards, adapted to longitudinal and transverse travel for operating on the pairs of projections of said cards, operating means for said card-moving members and a longitudinally and vertically movable member arranged beneath said operating means for actuating said operating means.
5. In a card finding and separating device, a receptacle containing a plurality of cards, a longitudinally movable member located beneath said cards, a member carried by said longitudinal member adapted to upward movement, a pair of card-moving members adapted to keep the same distance apart while travelling longitudinally and transversely beneath said cards, and means cooperable with said card-moving members adapted to be actuated by said member of said longitudinally travelling member.
6. In a card finding and separating device, a receptacle containing a plurality of cards, a member movable longitudinally beneath said cards bearing a series of upwardly movable elements, a pair of card-moving members located above each of said upwardly movable elements adapted to be moved longitudinally and transversely of the receptacle and a series of vertically movable members, each being cooperable with a respective element of said first-mentioned movable member and a respective pair of card-moving members.
7. A card finding and separating device comprising a receptacle adapted to contain a plurality of index cards, a carriage adapted to be moved transversely and longitudinally beneath said cards, and a pair of transversely arranged card-moving members reciprocally mounted in said carriage for operating on said cards.
8. In a card finding and separating device, a receptacle containing a plurality of cards each having a pair of equally distant spaced apart depending portions, a pair of transversely arranged card-moving members held apart a distance equal to the pairs of projections of each of said cards, and means for moving said pairs of card-moving members longitudinally and transversely beneath said cards.
9. In a card finding and separating device, a receptacle containing a plurality of cards each having a pair of equally distant spaced apart depending projections, the pairs of projections of said cards being in staggered relation to one another, a pair of transversely arranged card-moving members held apart a distance equal to that of the respective pairs of projections of said cards, and means for

moving said pair of card-moving members together transversely beneath said cards so that said card-moving members can engage the pair of projections of any one of said cards.

10. In a card finding and separating device, a receptacle, a plurality of upright cards mounted in said receptacle, a series of pairs of card-moving members held an equal distance apart transversely, all of said members adapted to be moved in unison longitudinally and transversely beneath said cards, a vertically reciprocating member located beneath each pair of said card-moving members for engagement therewith, a longitudinally movable member arranged beneath said vertically movable members bearing parts for cooperation with each of said vertically movable members, means for shifting said longitudinally movable member so that the co-operating parts thereof can be moved to positions of cooperation relative to any of said vertically movable members, and means for moving said cooperable parts upwardly so that one of said vertically movable members will engage a pair of card-moving members.

11. In a card finding and separating device, means for holding a plurality of cards in upright positions, a carriage bearing a pair of card-moving members arranged to travel longitudinally beneath said cards, controllable means for moving said carriage forwardly and rearwardly beneath said cards, and means for moving said carriage transversely of said cards.

12. In a card finding and separating device, means for holding a plurality of cards in upright positions, a carriage bearing a pair of card-moving members arranged to travel longitudinally beneath said cards, controllable means for moving said carriage forwardly and rearwardly beneath said cards, means for moving said carriage transversely of said cards, operating means for said card moving members, a member to travel longitudinally beneath said card-moving members related to said operating means, and controllable means for moving said last-mentioned member forwardly or rearwardly.

13. In a card finding and separating device, a plurality of cards, means for holding said cards in upright positions, a pair of card-moving members arranged beneath said cards adapted to longitudinal and transverse travel, a movable member located beneath said card-moving members extending the length of the longitudinal travel of said card-moving members, and a second movable member for applying upward movement to said first-mentioned movable member.

14. In a card finding and separating device, means for holding a plurality of cards in upright positions, a carriage bearing a pair of card-moving members arranged to travel longitudinally beneath said cards, con-

trollable means for moving said carriage forwardly and rearwardly beneath said cards, and locking means for holding said controllable means against movement.

15. In a card finding and separating device, means for holding a plurality of cards in upright positions, a carriage bearing a pair of card-moving members arranged to travel longitudinally beneath said cards, controllable means for moving said carriage forwardly and rearwardly beneath said cards, means for moving said carriage transversely of said cards, and locking means for holding said carriage against movement in either direction.

15 16. In a card finding and separating device, a plurality of cards, means for holding said cards in upright positions, a series of pairs of card-moving members arranged beneath said cards adapted to longitudinal and transverse travel, a lifting member located beneath each pair of said card-moving members for actuating said card-moving members, extending the length of the longitudinal travel of the respective pair of card-moving members with which it is adapted to cooperate, a movable member for applying upward movement to each of said lifting members, and means for moving all of said movable members together.

20 25 30 35 17. In a card finding and separating device, a receptacle containing a plurality of cards, a card-moving member for lifting a desired card of the plurality of cards, and means for engaging the lifted card so as to uphold said card after said card-moving member has been returned to its former position.

40 45 18. In a card finding and separating device, a receptacle containing a plurality of cards each having a recess formed in one of the side edges thereof, a card-holding member adapted to engage the recesses of said cards, and means for lifting a desired card from among said plurality of cards, said card-holding member adapted to be displaced from the recess of, and engaged beneath said lifted card.

50 55 60 65 19. In a card separating device, the combination of a longitudinally movable member, a carriage adapted to longitudinal and transverse travel, means for moving said carriage, a pair of card-moving members carried by said carriage having their card engaging portions spaced apart a given distance, means cooperable with said longitudinally movable member and said card-moving members for actuating said card-moving members, and locking means for preventing said carriage being moved during the operating of said card-moving members carried thereby.

65 20. In a card finding and separating device, a receptacle containing a plurality of cards, a series of pairs of card-moving mem-

bers arranged beneath said cards adapted to longitudinal and transverse travel, an independently movable lifting member located beneath each pair of card-moving members, each having a portion extending the length of the longitudinal travel of its respective pair of card-moving members, a longitudinally movable member having portions which are adapted to upward movement, each portion of said longitudinally movable member being adapted to cooperate with a respective lifting member, and means provided whereby all of said lifting members may be moved together for moving all of said card-moving members together.

70 75 80 85 21. In a card finding and separating device, a receptacle containing a plurality of upright cards, means for successively elevating any of said cards to positions wherein the upper edges thereof are above said other cards, and means for simultaneously returning all of the elevated cards to their neutral positions.

90 95 22. In a card finding and separating device, a receptacle containing a group of upright cards, a pair of card-moving members adapted to longitudinal and transverse travel beneath said cards to positions of engagement whereby said card-moving members can lift any one of said cards, and a lifting member for engagement with said card-moving members during any of the card-lifting positions of said card-moving members.

100 105 23. A mechanism for raising an edge of a desired card from a group of upright cards comprising a pair of related card-moving members adapted to transverse travel relative to the card group, a lifting member for said card-moving members, and means cooperable with said card-moving members and said lifting member whereby said lifting member is active on said card-moving members in any transverse location of said card-moving members.

110 115 24. A mechanism for raising the edge of a desired card from a group of upright cards, comprising a card-moving member having a transversely extending portion adapted to transverse travel relative to the card group, and a lifting member for engagement with said transversely extending portion of said card-moving member.

120 125 130 25. A mechanism for raising the edge of a desired card from a group of upright cards, comprising a card-moving member having a transversely extending portion adapted to transverse and longitudinal travel relative to the card group, and a lifting member for engagement with said transversely extending portion of said card-moving member having a longitudinally extending portion for underlapping the transverse extending portion of said card-moving member during its longitudinal travel.

26. In a card finding and separating device, a receptacle containing a plurality of upright cards, means for elevating a number of said cards to positions wherein the edges of said cards are above said cards, and movable means above said cards for simultaneously returning the elevated cards to their neutral positions. 70
27. In a card finding and separating device, a receptacle containing a group of approximately vertically held cards, each of said cards having a pair of equidistantly spaced apart depending projections, the pairs of projections of said cards being in staggered relation to one another. 75
28. A mechanism for raising an edge of a desired card from a group of upright cards comprising a swingable card-moving member having a transversely extending portion and adapted to transverse travel relative to the card group, and a swingable lifting member for engagement with said transversely extending portion of said card-moving member. 80
29. A mechanism for raising an edge of a desired card from a group of upright cards comprising a pair of relatively swingable card-engaging members adapted to transverse travel beneath the card group, and a rockable lifting member for actuating said swingable card-engaging members. 85
30. A card finding and separating device comprising a receptacle containing a plurality of upright cards, a carriage adapted to longitudinal and transverse travel beneath said cards bearing a series of swingable pairs of card-moving members, a rockable element longitudinally arranged beneath said cards bearing a series of lifting members, each being for operation on a respective pair of said card-moving members, and a second rockable element adapted to longitudinal travel, bearing a series of projections, each of said projections adapted to successively engage a respective lifting member of said first-mentioned rockable element. 90
31. In a card finding and separating device, a plurality of cards, means for holding said cards in upright positions, a series of pairs of card-moving members arranged beneath said cards adapted to longitudinal and transverse travel, a lifting member located beneath each pair of said card-moving members for actuating said card-moving members, extending the length of the longitudinal travel of the respective pair of card-moving members with which it is adapted to cooperate, and a movable member for applying upward movement to each of said lifting members. 95
32. In a card finding and separating device, a receptacle containing a plurality of upright cards, means for successively elevating any of said cards to positions wherein the upper edges thereof are above said other cards, and means comprising a pressing element to be engaged against the upper edges of the elevated cards for simultaneously returning the elevated cards to their neutral positions. 100
